J. C. PALMER

OIL PUMP

Filed May 8, 1923

Inventor

Joe C. Palmer.

By *A. L. Jackson*
Attorney

UNITED STATES PATENT OFFICE.

JOE C. PALMER, OF FORT WORTH, TEXAS.

OIL PUMP.

Application filed May 8, 1923. Serial No. 637,472.

To all whom it may concern:

Be it known that I, JOE C. PALMER, a citizen of the United States, residing at Fort Worth, in the county of Tarrant and State 5 of Texas, have invented certain new and useful Improvement in Oil Pumps, of which the following is a specification.

My invention relates to gasoline feed pumps and more particularly to an electrically operated coin-controlled pump; and the object is to provide a simple device which can be operated by the customer without the attention of the owner or proprietor and to provide a simple mechanism which 15 can be installed at small cost and which can be operated without expense of an attendant. Other objects and advantages will be fully explained in the following description and the invention will be more particularly 20 pointed out in the claims.

Reference is had to the accompanying drawings which form a part of this application.

The figure of drawing is a diagrammatic 25 view with certain parts shown in section.

The apparatus is provided with a tank 10 and a supply or filling pipe 19 is connected to the tank 10 and to a supply source. The tank 10 is also provided with a discharge pipe 18. The inlet to the tank 10 is opened and closed by a valve 8 and the outlet is opened and closed by a valve 9.

Electrical means are provided for controlling and opening the valves 8 and 9. 30 Stationary electro-magnets 6 and 16 are provided and a movable electro-magnet 5 is provided. A coin chute 1 is provided and the coin chute runs through a contact 2. A plunger 20 is used to push the coin through 35 the chute 1. As the coin is forced against and past the contact 2, the circuit is completed through the wire 4 to electro-magnets 5 and 6. When the magnets 5 and 6 are energized, the magnet 5 will be drawn to 40 magnet 6. The magnet 5 is suspended on a pivoted bar 21 which has a pivotal mounting 7. The bar 21 actuates a horizontally disposed valve control rod 22. The rod 21 is connected loosely to the valve control 45 rod 22 for moving this rod horizontally for actuating the valves 8 and 9. When the magnets 5 and 6 are energized through the current wire 4, the magnet 5 will carry the

bar 21 and this bar will slide the control rod 22 to the right as the devices are illustrated in the drawings and so open the valve 8 and close the valve 9. When the tank 10 is nearing the filling point, or the gasoline rises until the float 13 rises against the contact 14, a circuit is closed through contact 2, wire 12, contact 14, wire 15 and magnets 16 and 5. These magnets will be energized and the magnet 5 will be drawn to magnet 16. The control rod 22 will be actuated and the valve 8 will be closed and the valve 9 will be opened. (The contact 2 and the wire 4 will be disconnected as soon as the coin passes the contact 2 and the coin will fall into a box 3.) When the valve 9 is opened, the charge of gasoline will be 50 delivered through the discharge pipe 18 to the customer.

A spring 23 is attached to the inside of the contact members 2 for bearing on the coin and retarding the same and to maintain the contact of the wires for a sufficient length of time to shift the magnet 5. The spring 23 will make the contact more certain as the free end of the spring will project in the path of the coin.

What I claim, is,—

1. A liquid feeding device comprising a tank provided with inlet and discharge valves, two stationary magnets and a swinging magnet positioned between and spaced from said stationary magnets, a lever carrying said swinging magnet, a sliding bar provided with lugs projecting in the path of the short end of said lever, means for energizing one of said magnets and said swinging magnet for actuating said lever to open the inlet valve and to close the discharge valve, and means to be actuated by liquid accumulating in said tank for energizing the other stationary magnet and said swinging magnet for actuating said lever and bar to close said inlet valve and to open said discharge valve.

2. A liquid feeding device comprising a tank provided with inlet and discharge valves, two stationary magnets and a swinging magnet positioned between and spaced from said stationary magnets, a lever carrying said swinging magnet, a sliding bar provided with lugs projecting in the path of the short end of said lever and connected to

said valves, coin-actuated electrical devices for energizing one of said stationary magnets and said swinging magnet for actuating said lever and bar to open said inlet valve and to close said discharge valve, and means to be actuated by liquid accumulating in said tank for energizing the other sta-

tionary magnet and said swinging magnet for actuating said lever and bar for closing said inlet valve and for opening said discharge valve. 10

In testimony whereof, I set my hand, this 30th day of September, 1922.

JOE C. PALMER.
